UNITED STATES PATENT OFFICE.

GEORGE W. GWINN, OF NEW YORK, N. Y., ASSIGNOR TO AUTOMATIC PACKING & LABELING COMPANY, OF DURHAM, NORTH CAROLINA, A CORPORATION OF NORTH CAROLINA.

DRYING APPARATUS FOR STAMPS, LABELS, OR SEALING-STRIPS.

1,074,358.

Specification of Letters Patent.

Patented Sept. 30, 1913.

Application filed January 20, 1911. Serial No. 603,717.

To all whom it may concern:

Be it known that I, GEORGE W. GWINN, a citizen of the United States, residing at New York, in the county of New York and State of New York, have invented certain new and useful Improvements in Drying Apparatus for Stamps, Labels, or Sealing-Strips, of which the following is a specification.

10 My present invention pertains to an improved drying apparatus for stamps, labels, or sealing strips employed in conjunction with packaged materials. In the application of such articles to packages which are usually folded or closed in at the end, difficulty is experienced, by reason of the fact that the stamp, label or the like will become loose and, if such stamp be depended upon to hold the package closed or sealed, the 20 package will open or be readily accessible.

The main object of the present invention is to provide means for holding the stamp in position until the paste or other adhesive which is employed to secure it in place is 25 fully set or dry and, at the same time, to provide a structure which will readily permit the stamped packages to be fed therethrough as they are delivered from a packaging machine.

30 A further object of the invention is to so construct the mechanism that a minimum amount of drag will be exerted upon the stamps as the stamped packages are passed through the machine, and also to permit 35 those portions of the mechanism which are liable to become coated or clogged with adhesive to be quickly withdrawn and as quickly replaced by a clean substitute part.

With these and other objects in view, a 40 description of the invention will be given, reference being had to the annexed drawings, wherein:

Figure 1 is a side elevation of the mechanism; Fig. 2 a transverse sectional view, on 45 the line 2-2 of Fig. 1; Fig. 3 an elevation of the package-delivering mechanism and one of the transfer bunters; Fig. 4 a top plan view of the mechanism as a whole; Fig. 5 a perspective view of one of the roll-carrying frames which form the upper portion 50 of the runway for the packages when they are being moved through the machine be-

tween the drying plates; and Fig. 6 a perspective view of one of the drying and pressing plates.

55

The mechanism shown in the drawings and herein described is designed especially for use in conjunction with a weighing and packaging machine, such as is illustrated in my copending application Serial No. 506,579 60 filed on or about the 8th day of July, 1909. It may, however, be used in connection with any other machine in which a stamp, label or strip is applied and held by an adhesive.

In the drawings, 1 denotes the completed 65 package and 2 the stamp, which has been applied to the upper infolded end thereof, the ends of the stamp extending down the sides of the package, as best shown in Fig. 1. The term "stamp" will hereinafter be employed, though it will be understood as being the equivalent of a label, sealing-strip or the like.

The package is brought to the position shown in Fig. 3 between the elevator or 75 bunter 3 and the stamp-holder 4, said holder in the present instance being shown as provided with a series of rollers 5 in its under surface, which bear upon the previously-positioned stamp. The stamp to which the adhesive is applied is, prior to being brought to the position shown, drawn over the upper end of the package and then moved upward by the elevator 3 between suitable devices which wipe the ends of the stamps down 85 over the side edges of the package. When the stamped package reaches the position shown in Fig. 3 bunter 6 moves the same laterally onto a table 7, preferably provided with a planished metallic face or plate 8. 90 As the package travels onto the table it likewise passes beneath a series of rollers 9, carried in a frame 10, which is removably mounted in a bracket 11. The elevator and stamp-holder, after the bunter 6 is withdrawn, move downwardly to bring another package to place. The bunter 6 carries the package to the position shown in Fig. 3, in line with a bunter or pusher 12, which works at right angles to the bunter 6 and in line 100 with the table 7. The pusher 12 comes into action after bunter 6 has been withdrawn, and acts to advance the package along the table beneath a series of rollers 13, mounted

in the lower face of a frame 14, the upper face of the frame being formed with a rib 15. Said rib, when the frame is positioned (see Fig. 2) is engaged by two L-shaped bars 16 and 17, said bars being secured to brackets 19 and 20, which in turn are secured at their lower ends to the table, or more specifically, to one of the side walls 21 thereof. The roll-carrying frame 14, as will 10 be best seen upon reference to Fig. 1, extends well back toward the roll-frame 10 and both of said frames are readily removable from their supports, so that others may be substituted in their place as occasion 15 requires or when the rollers become sticky or gummed by adhesive which exudes from beneath the stamps.

Secured to the upper face of the rails or bars 16 and 17 and extending to each side 20 thereof is a pair of brackets 22 and 23, the ends of the brackets being bifurcated and adapted to form the supports for the levers or arms which carry and actuate the drying and pressing plates, of which there are two, 25 one adapted to act upon one end of the stamp and the other upon the opposite end as the packages are moved along the table. Each plate comprises an elongated metallic casting 24, the inner face of which is perfectly smooth, and the extremity adjacent to the receiving end of the table is inclined or beveled downwardly, as at 25. The plate in the form illustrated is provided with a pair of lugs 26 and 27, adapted to receive 30 and hold a gas-pipe 28, provided with a series of openings 29, directed toward the plate. A cover-plate 30, having inturned ends 31, is hinged to the upper flange of the plate 24, the lower portion of said cover-plate lying against the pipe, as shown in 35 Fig. 2, thereby forming a substantially closed chamber which confines the heat against the presser-plate 24. Any form of heater may be employed, as for instance, an electric heater, which in practice has been successfully used. Each plate 24 is provided with a hinge lug 32 adapted to pass 40 between the bifurcated ends of bracket 23 and to be pin-jointed thereto. A lever 33 also extends upwardly from the plate adjacent to its beveled end, said lever being formed with an opening 34 through which a pin may be passed to secure the hinge joint and lever to the bracket 22. The 45 oppositely-disposed levers of the plates, which for the sake of clearness are designated by 33 and 33^a, are connected to each other through a coil spring 35, secured to the upper ends of the levers, said spring tending 50 to draw said ends together and consequently to throw the drying and pressing plates 24 outwardly or away from each other. To move said plates inwardly or into position where they will contact with and press 55 against the stamp ends, the following

mechanism is employed: Secured to lever 33^a is an inwardly-extending arm 36 carrying at its outer end an adjustable screw 37, the lower end of the screw contacting with the outer end of an arm 38 secured to 70 lever 33. Swiveled upon the upper end of lever 33 is a yoke 39, connected through an adjustable link 40 with a yoke 41 which in turn is connected to the short arm 42 of a lever fulcrumed upon a shaft 43 carried by 75 the brackets 19 and 20. The lower or longer arm 44 of the lever is connected to the oper- or stamp-applying mechanism, as the case may be.

From the foregoing it will be seen that as 80 the upper end 42 of the lever is thrown inwardly the upper end of lever 33 will likewise be moved inwardly and the outer end of arm 38 moved downwardly, at the same time moving the pressing and drying plate 85 to which the lever 33 is attached outwardly. Spring 35 being under stress will rock lever 33^a and consequently throw its plate outwardly simultaneously with the outward movement of the opposite plate. A reverse 90 movement of lever 42 will throw arm 38 upward and, through screw 37, raise arm 36 and force the upper end of lever 33^a outwardly, thereby swinging its plate inwardly into pressing position as the opposite plate 95 is brought into like relation. It will thus be seen that the plates are opened and closed simultaneously and by adjusting the link 40 and the screw 37 may be made to exert the desired degree of pressure upon the stamp. 100

The various parts, such as the elevator, bunters and presser-plates, are all timed to work in their proper sequence, so that while a package is being brought to position by the elevator 3 the hot or warm presser plates 105 will be momentarily opened or separated, and pusher 12 will advance and move the previously-deposited packages along the table 7 a distance equal to the thickness of one package, or slightly more. When this is accomplished, the pusher is moved away and the presser plates close in upon the stamp ends. While these members are at rest, bunter 6 advances a package just positioned by the elevator or lifter 3 from beneath rollers 5 to and beneath rollers 9 in front of the pusher 12. Bunter 6 is then retracted and the same cycle of operations as above set forth is repeated. 110

It will be noted from the foregoing de- 120 scription that the stamp, or at least the upper or central portion thereof, is constantly held under rollers and this does away with any drag on the stamp and consequent misplacement thereof. Furthermore, as the 125 package is moved along the table, the ends of the stamps, if they should become curled outwardly, will come in contact with the beveled ends 25 and be smoothed down against the package. As will be seen upon 130

reference to Fig. 6, the upper portion of the beveled edge 25 will contact with the stamp nearest the upper portion of the package, and as the package is moved inwardly along 5 said edge the downward inclination of the edge will tend to draw or wipe the stamp downward against the side of the package. When once between the plates there is no chance for the stamps to curl as the plates 10 are only separated momentarily. By the time the packages have passed from between the plates, the stamps will be perfectly dry or the adhesive set to such a degree as to firmly hold the stamp in place.

15 By having the roll-carrying frames readily removable a clean set of rolls may be quickly substituted for a set which may have become sticky or gummed from the exceeding adhesive.

20 As above noted, the term "stamp" used herein and in the appended claims is to be treated as a generic term.

Having thus described my invention, what I claim is:

25 1. In a machine for drying the ends of stamps applied to packages, the combination of a package-support; means contacting with the end portions of the stamps lying against the sides of the packages for pressing the ends against the packages; and mechanism for heating said means.

30 2. In a machine for drying stamps applied to packages, the combination of a support or runway adapted to sustain a plurality of packages; means movable toward and from the opposite sides of the packages in line with the stamp-ends thereon to press the same against the sides of the packages; and mechanism for heating said pressing means.

35 3. In a machine for drying stamps applied to packages, the combination of a package-support; means located upon opposite sides of said support movable toward and from the stamp-ends and adapted to press the ends against the opposite sides of the package; mechanism for heating said means; and means for advancing the packages along the support when the pressing means is in its retracted position.

40 4. In a machine for drying stamps applied to packages, the combination of a support for the packages; a pair of swinging plates located upon opposite sides of the support; means for heating said plates; and means for swinging the plates into and out of contact with the ends of the stamps upon the opposite sides of the package.

45 5. In a machine for drying stamps applied to packages, the combination of a runway adapted to support a plurality of packages; a pair of swinging plates located upon opposite sides of the runway; means for heating said plates; means for swinging the plates into and out of contact with the ends of the stamps; and means for

advancing the packages along the support when the plates are in their retracted position.

6. In a machine for drying stamps applied to packages, the combination of a runway adapted to support a plurality of packages; means located above the runway and bearing upon the central portion of the stamps which overlie the upper end of the packages; and heated means movable toward and from the sides of the packages to press the stamp-ends against the packages and cause the stamp-ends to dry in place. 70

7. In combination with a support for stamped packages; means acting on the opposite sides of the package to position the stamp-ends and a plurality of rollers arranged above the support and adapted to bear upon that portion of the stamp which extends over the top of the package. 80

8. In combination with a support for stamped packages; means acting on the sides of the package to position the stamp-ends; and a removable frame provided with a plurality of rollers arranged above the support and adapted to bear upon that portion of the stamp which extends over the top of the package. 90

9. In a machine for drying stamps applied to packages, the combination of a package-support or runway adapted to sustain a plurality of packages; means for advancing the packages step by step along said runway; and heated means contacting with the stamps upon the packages supported upon the runway, while the same are at rest thereon. 95

10. In a machine for drying stamps applied to packages, the combination of a support or runway adapted to sustain a plurality of packages; means for advancing the packages step by step along said runway; relatively movable heated devices contacting with the stamp-ends upon the packages; and mechanism for effecting such relative movement, said mechanism separating said devices as the package-advancing means comes into operation. 105

11. In a machine of the character specified, the combination of a table or support for packages; a frame removably mounted above the same; a plurality of rollers mounted in the frame; a pair of heated presser-plates movable toward and from the packages held between the table and the rollers; and means for actuating said plates. 115

12. In a machine of the character specified, the combination of a support for the stamped packages, and a heated presser-plate, the forward edge of which is inclined downwardly, whereby the out-curling edge of the stamp will be turned down. 125

13. In a machine of the character specified, the combination of a table; supporting members located above the same; a frame re- 130

movably connected to said members; a series of rollers carried by the frame; a pair of swinging presser-plates located upon opposite sides of the frame; means for heating the plates; and means for actuating said plates.

14. In a machine of the character specified, the combination of a table; a supporting plate located above the same; a frame 10 movably connected to said plate; a series of rollers carried by the frame; a pair of levers fulcrumed adjacent to the plate; a presser plate carried at the lower end of each lever; means for heating said plates; 15 means for drawing the upper ends of said levers together and thereby throwing the plates apart; and means for separating the upper ends of said levers and thereby throwing the presser plates toward each 20 other.

15. In a machine of the character specified, the combination of a table; a supporting plate located above the table; a frame 25 removably mounted upon said plate; a series of rollers carried by said frame; a pair of levers fulcrumed at a point adjacent to the plate; a presser plate carried at the lower end of each of said levers; means for heating said plates; a spring serving to 30 draw the upper ends of said levers together and thereby to separate the presser plates; an arm extending out from each of said levers, one arm overlying the other; a screw

adjustably mounted in one of said arms and bearing upon the other arm; and means 35 connected to one of said levers for moving the same and thereby, through the arms and screw, moving the other lever in opposition to the action of the spring.

16. In a machine of the character specified, the combination of a package-presenting mechanism; a table; a plurality of rolls located above the table and adapted to contact with the upper end of the package as the same is moved onto the table; means for 45 transferring the package onto the table beneath said rolls; a second series of rolls located above the table; means for transferring the package from the first set of rolls along the table and beneath the second series of rolls; presser plates adapted to contact with the ends of the stamps upon the packages as they pass beneath the second series of rolls; and means for periodically 50 separating said plates from the packages and moving the same into contact with the stamps on the packages while the packages are at rest.

In testimony whereof, I have signed my name to this specification in the presence 55 of two subscribing witnesses.

GEORGE W. GWINN.
